UNITED STATES PATENT OFFICE

CORANNE MACGREGOR, OF CLEVELAND HEIGHTS, OHIO

CONSTRUCTION OF SMALL ORNAMENTAL FIGURES OR DOLLS

Application filed July 13, 1929. Serial No. 378,075.

This invention relates to the construction of small ornamental figures or dolls, constructed mainly from paper or paper products, and suitable for use as decorative novelties, favors and the like. Forms of any kind can be developed by means of the invention, especially such figures or forms as dolls, animals, and birds.

The invention embodies a new method of building up the various figures, and this method may be explained by printed directions accompanying the material, which may be cut, printed or stamped in advance, and which will enable any person with a little skill to build up various forms or figures of novel and attractive appearance.

Mainly the structure embodies, first, a skeleton or internal frame or frames; second, paper pads or wads mounted thereon; and third, a suitable skin or other covering, which may be made of paper or other material, printed or cut in advance. The completed object or figure is very light in weight and costs but little, but will nevertheless stand considerable handling.

The invention is illustrated in various forms in the accompanying drawings in which Fig. 1 is a front elevation of a doll skeleton or internal frame. Fig. 2 is a side elevation of the arm frame. Fig. 3 is a side elevation of the torso structure or frame of the doll. Fig. 4 is a similar elevation of the leg frame. Fig. 5 is an elevation of a joint structure. Fig. 6 is a plan of the blank from which it is made. Fig. 7 is a plan of the foot frame. Fig. 8 is an illustration showing the method of wrapping paper around a frame to make a finished structure. Fig. 9 is a front elevation of an animal head showing pads or stuffing in position to make the same. Fig. 10 is a side view of an animal head with pads in place. Fig. 11 is a side elevation of a completed doll. Figs. 12 and 13 are similar views of a bird and an animal.

In the illustrations shown the torso frame comprises a paper or cardboard sheet 1, somewhat stiff or rigid, cut to suitable form and upon this is placed a series of vertical paper or cardboard pieces 14, 15 and 16, extend-

ing from front to back. These sections or pieces may be pasted or otherwise attached to the piece 1, or preferably by having slots in each piece, halved so that the pieces will slip together at right angles to each other. 55 Similarly horizontal cross pieces 6 and 7 intersect the other pieces at slots indicated at 29 and 30. The result is the formation of a torso skeleton or frame divided by the vertical and horizontal pieces into a plurality 60 of cells or spaces into which pads are to be placed as hereinafter described, the edges of the pieces defining the outlines of the form or body to be built up.

Similarly the arm sections shown in Fig. 65 2 are constructed of an upper arm piece 2, a lower arm piece 3, longitudinal pieces 17 and 17', and cross pieces 8, 9 and 10, slipped or joined together by means of "halved" slots or otherwise to produce the outline of the 70 member.

The leg frame shown in Fig. 4 similarly comprises pieces 4 and 5, longitudinal cross pieces 8, and horizontal cross pieces 11 and 12. The foot frames comprise flat blanks 75 13 with flanges or ribs 31 thereon.

The frames of other objects or animals are constructed in a similar manner, that is by intersecting blanks or pieces extending through slots or slits in each other at the intersections, or otherwise attached to project in different planes and form cavities or cells between such pieces. The pieces may be marked in advance to indicate how they are to be slotted in building up the frame. 85

The separate members thus constructed may be articulated in various ways. A neck for example may comprise a neck tube 20 inserted over the neck piece 1^a of the torso and fastened in place by gummed tape indicated at 20^a. The elbow and knee joints may be made of cuffs 21 bent around the joints and stuck together by a gummed section at the end of the cuff blank. The arm and leg frames are fastened together and to the torso by wires 22, 23, 24 and 25 which may be inserted through suitable holes provided or made in the frame pieces where they intersect, the leg wires 22 and 23 preferably crossing each other at 28 and having hooks 100

26 and 27 at their upper ends which engage the neck tube 20 and having hooks 32 at their lower ends which hook into the flanges 31 of the foot frames. And the arm wire 25 is hooked at 33 and 34 into the member 17' of the arm frames, and the wire 25 is hooked as at 35, from the rear, around the shoulders of the arm wire 24. A frame thus constructed will be joined together with sufficient flexibility at the joints to permit the wires to be bent to extend the arms or legs in various directions. Additional fastenings consisting of gummed tapes may be applied if and whenever necessary.

15 In the animal figures shown for example in Fig. 10 the longitudinal and cross frames 38 and 39 may be bent or assembled to the proper outlines.

16 The next step in the formation of the body or figure is the insertion of the paper pads 40 in the cells or spaces produced by the angular frame pieces. These pads preferably consist of tissue paper crumpled or crushed to form light wads or pads which may be dipped in glue and are then stuck in the cells to fill out the body or member and give it suitable form and proportions.

17 Then the body and members so formed are wrapped with crepe or other paper strips 36 glued in place. Or, for the smaller members, the padding may be omitted, the paper strips 36 wrapped directly around the frame as shown in Fig. 8. Or, a cover or skin of paper or other material, such as indicated at 35 42 in Fig. 2 and 43 in Fig. 13, may be applied and glued in place, and this covering or skin may be printed or otherwise designed to represent the animal or other form desired.

18 By the method described, or modifications thereof, various structures may be quickly and cheaply produced, from blanks prepared or cut in advance, and suitable pads, of tissue or crepe paper, and other adjuncts suitable for the particular objects to be constructed. 105
19 The figures constructed will be cheap and light and very suitable for the purposes referred to as well as for educational purposes by enabling children or others to build up various animal, bird and other forms.

20 I claim:

1. An ornamental figure comprising an internal frame consisting of pieces crossed to form spaces therebetween, pads in said spaces between the pieces, said pads cooperating with the periphery of said pieces to define the shape of said figure, and an external covering applied thereto.

2. An ornamental figure comprising an internal frame having cells, pads in said cells, said pads cooperating with the periphery of said frame to define the shape of said figure, and an outer covering inclosing the same.

3. An ornamental figure comprising an internal frame consisting of cardboard pieces 125
25 intersecting each other and forming spaces

between the pieces, pads of crumpled paper in said spaces, said pads cooperating with the periphery of said pieces to define the shape of said figure, and an outer covering applied around the same.

4. An ornamental figure comprising pieces of thin material assembled at angles to each other to form an internal frame outlining the figure, the frame having cells between said pieces, paper pads filling said cells, said pads cooperating with the periphery of said pieces to define the shape of said figure, and a covering of flexible fabric inclosing said frame and pads.
